MEMO RECORDER

Bernard Alvin Barrett, Vancouver,
British Columbia, Canada

Application June 24, 1946, Serial No. 678,722

19. Claims. (Cl. 282—15)

1

This invention relates to a device for providing a record roll on which notes may be made, or slips for this purpose while making a record of any notes made on the slips.

A great many people who work in offices and other places of business make numerous notes on scratch pads or slips of paper throughout the day, usually as reminders to do certain things. There is no way of checking whether everything has been done and if a slip is lost or misplaced, the work is not done. Furthermore, there is no way of checking to ascertain whether the full instructions have been complied with.

The object of the present invention is the provision of a device adapted to provide a record roll on which notes may be made, or slips of paper on which notes may be made in the ordinary way and which makes a record of the notes so that a person may periodically check back to see whether or not everything has been done. The device may also be turned back in order to make sure that the instructions have been properly carried out, or for any other purpose.

This memo recorder provides slips of a paper of any desired length or slips of a predetermined length upon which notes may be made. At the same time, these notes are transferred to another piece of paper which is wound on to a roll so that it will be available when desired.

The invention is illustrated by way of example in the accompanying drawings, in which

Figure 1 is a perspective view of the memo recorder,

Figure 2 is a side elevation with the near side removed,

Figure 3 is a plan view of the device with the top removed and certain parts omitted for the sake of clarity,

Figure 4 is a fragmentary perspective of one end of the recorder with some parts removed,

Figure 5 is a side elevation similar to Figure 2 of one end of an alternative form of the invention,

Figure 6 is a fragmentary plan view of part of the alternative shown in Figure 5, and

Figure 7 is a fragmentary side elevation of still another form of the invention.

Referring more particularly to the drawings, 10 is a casing of any desired shape having side walls 11 and 12 and a top 13. Most of the bottom of the casing is open, but it has at one end a bottom 14 hingedly mounted at 15 on the inside of the walls 11 and 12. The top 13 has spaced transverse slots 16 and 17 formed therein, and spaced guides 18 extending longitudinally thereof from points adjacent each end of the slot 16 part way

2

towards the slot 17. The slot 16 acts as a tearing edge, as will hereinafter appear.

A roll of paper 21 is removably mounted in one end of the casing on a transverse bolt or shaft 22, and a strip of paper 23 from said roll extends between relatively large flanges 24 and beneath a core 25 mounted on a transverse shaft or bolt 26, over a transverse roller 27 mounted near the top of the casing substantially midway between the ends thereof, and around another transverse roller 28 mounted near the opposite end of the casing adjacent the top thereof. After passing around the roller 28, the strip 23 emerges through the slot 16 as strip 29, passes over the top 13 beneath the guides 18, down through slot 17, over a roller 30 located near the top of the casing above and between the shafts 22 and 26, and down between the flanges 24 on to the core 25. This core has a slot 31 formed therein adapted to receive the end of the strip of paper so that the latter may be wound thereon. The strips 23 and 29 form a record strip for the device.

With this arrangement, the record strip may be unwound from the roll 21 and after it passes over the top 13 of the casing, it is wound on the core 25. The flanges 24 are fixed to and rotate with the core 25, and act as guides for the paper as it comes off the roll 21 and both before and while it winds on the core 25. It will be noted that the flanges 24 overlap the roll 21 so that it is impossible for the record strip to get out of alignment between this roll and the core 25 so long as the paper in the roll is overlapped by the flanges. This overlapping condition can be made to continue as long as desired, depending upon the diameter of the flanges and the size of paper roll used.

The head 35, see Figure 3, of the shaft or bolt 26 is countersunk in a boss 36 formed on the inner surface of the wall 12. The opposite end of the bolt is threaded into a sleeve 37 which extends through a boss 38 formed on the outer surface of the wall 11. This sleeve has an annular shoulder 39 formed on its inner end which acts as a spacer for the adjacent flange 24, while a knob 40 is fixedly secured to the outer end of said sleeve. When the bolt is tightened, the head is drawn against flange 24 and the sleeve 37 is drawn in the opposite direction so that the flanges and core form a single unit which may be rotated by means of the knob 40. One or both of the flanges 24 are removable from the core 25 in order that when the bolt 26 is withdrawn, any paper which is rolled on the core may be removed therefrom.

The bolt 22 is mounted in the same way as the bolt 26, but, if desired, a dished washer 41 may be provided inside the wall 11 and a felt ring 42 may be located between the boss 38 and a knob 43 by means of which the roll 21 may be turned. The washer and felt ring form a friction assembly which prevents the roll 21 from turning too freely. A handle 44 pivoted to the knob 43 may be provided in order that the latter may be turned relatively fast. Thus, the knob 43 may be turned to move the paper from the roll 21 to the core 25, and the knob 43 turned to reverse this movement. The fact that the record strip passes beneath and contacts the core 25 or the paper wound around the latter keeps the record strip under tension and helps to prevent it from moving or bunching up when not required.

A U-shaped yoke 46 is mounted at its open end on a pin 47 which is carried by the sides of the casing 10 near its bottom beneath the slot 16. This yoke has upwardly extending projections 48 which carry a transverse shaft 49 on which one or more rubber rollers 50 are mounted. A spring 51, see Figure 2, normally urges the inner end of the yoke upwardly and, consequently, tends to keep the rollers 50 away from the roller 28, but said end may be depressed until the rollers 50 are pressed against the roller 28 or against any paper passing therebetween. A handle 52, see Figure 3, extends from the inner end of the yoke through a slot in the side 12, whereby the end of the yoke may be depressed.

A roll of paper 55 rests on the bottom 14 in a compartment formed by said bottom and spaced cross members 56 which may be supported from the sides of the casing, as shown, or from the bottom 14. Spacers 56a prevent endwise movement of this roll. A strip of paper 57 extends from this roll over a platform 58 mounted on the bottom 14 between vertical guides 59, between the rollers 28 and 50 beneath the strip 23, through the slot 16, and up over the top 13 between the guides 18, where it terminates. This strip forms a memo strip, and suitable transfer means is provided between it and the strip 23. For example, the memo strip may be carboned on the side thereof facing the strip 23.

Normally, when the knob 40 is turned to wind the record strip from the roll 21 on to the core 25, the memo strip 57 does not move. The weight of the roll 55 on the bottom 14 creates sufficient friction to prevent this paper from moving when it is not required. However, when the handle 52 is depressed, the rollers 50 press the memo strip against the record strip and the roller 28, so that said strips move in unison. When notes are made on the memo strip, they are inscribed on the record strip so that when a slip is torn from the memo strip, the notes are permanently recorded on the other strip. The knob 43 may be turned to unwind any amount of the record strip from the core 25 in order that the notes thereon may be reviewed.

The memo strip 57 may move only while the handle 52 is depressed, as described above, or suitable means may be provided for producing slips of a predetermined size. Figures 2 and 4 illustrate one means of accomplishing this. A gear 63 is mounted on one end of the shaft 49 and meshes with another gear 64 mounted on the end of a transverse shaft 65 carried by the yoke 46. This latter shaft has a finger 66 on its opposite end which is adapted to engage one end of a lever 67 mounted on a pivot shaft 68 which is carried by the sides 11 and 12. The

lever 67 has a shoulder 69 adapted to fit over a portion of the handle 52 which projects outwardly from the yoke to hold down the inner end thereof. A spring 71 normally urges said shoulder towards the handle, and the lever is provided with a face 72 which bears against the handle 52 when the inner end of the yoke is not depressed.

When the yoke is depressed by means of the handle 52, said handle moves downwardly off the face 72 of the lever 67 until it is engaged by the shoulder 69. Thus the yoke is locked down until the finger 66 moves around and pivots the lever 67 to disengage the shoulder from the handle and allowing the spring 51 to return the yoke to its normal position. A counterweight 73 may be provided on the shaft 65 to ensure the finger 66 moving past the lever 67 after it has released the yoke.

When the yoke is depressed in this manner, the memo strip feeds with the record strip until a slip of a predetermined size is produced on the top of the casing. As the gears 63 and 64 are turning while this is being done, the finger 66 moves around to cause the handle 52 to be disengaged, thus freeing the memo strip from the record strip.

Figures 5 and 6 show means for producing a memo slip of indefinite length without the necessity of holding the handle 52 down while it is being done. In this case, a shaft 75 extends across the casing near the inner end of the yoke and has a projection 76 overlapping said yoke. The rod 75 has a handle 77 outside the casing which may be depressed to cause the projection 76 to depress the yoke. Suitable means, such as a boss 78, is provided for retaining the handle 77 down until it is moved upwardly again. Thus the slip is continuously formed until this handle is raised.

Figure 7 illustrates one way of turning the core 25 faster than it can be done by means of the knob 40. A ratchet wheel 80 is mounted on the shaft 26 and it is engaged by a spring-loaded pawl 81 pivotally mounted on a lever 82 which is pivoted at 83 on the wall 11 and is offset to extend through a slot 84 in said wall. A spring 84 normally holds the inner end of the lever 83 down. When the outer end of this lever is depressed, the pawl 81 rapidly turns the ratchet wheel 80 which rotates the shaft 26 and the core 25.

What I claim as my invention is:

1. A memo recorder comprising a casing, means in the casing for receiving record paper in strip form, rotatable means in the casing for receiving the record strip from the first means, means for rotating the rotatable means to move the strip thereupon, a portion of said strip being exposed outside the casing, means for receiving memo paper in strip form, said memo strip extending out of the casing and overlapping at least a portion of the exposed part of the record strip, transfer means between the overlapped strips, and means for selectively pressing the strips together to cause the memo strip to move in unison with the record strip.

2. A memo recorder according to claim 1 including means for automatically stopping the movement of the memo strip after it has moved a predetermined distance.

3. A memo recorder according to claim 1 including means for causing the memo strip to move with the record strip until said means is released.

4. A memo recorder comprising a casing, means in the casing for receiving record paper in strip form, rotatable means in the casing for receiving the record strip from the first means, means for rotating the rotatable means to move the strip thereupon, a portion of said strip being exposed outside the casing, means for receiving memo paper in strip form, said memo strip extending out of the casing and overlapping at least a portion of the exposed part of the record strip, transfer means between the overlapped strips, a roller in the casing over which the memo and record strips pass before emerging from the casing, and means for selectively pressing the said strips together and against the roller to cause the memo strip to move in unison with the record strip.

5. A memo recorder comprising a casing, means in the casing for receiving record paper in strip form, rotatable means in the casing for receiving the record strip from the first means, means for rotating the rotatable means to move the strip thereupon, a portion of said strip being exposed outside the casing, means for receiving memo paper in strip form, said memo strip extending out of the casing and overlapping at least a portion of the exposed part of the record strip, transfer means between the overlapped strips, a roller in the casing over which the memo and record strips pass before emerging from the casing, a yoke pivotally mounted at one end in the casing beneath the roller, at least one roller mounted on the yoke above its pivot adjacent the first roller, and spring means normally retaining the yoke with its roller away from said first roller, said yoke being movable to cause its roller to press the memo and record strips together and against the first roller.

6. A device according to claim 5 including means for retaining the yoke with its roller pressing the memo and record strips together a predetermined time.

7. A device according to claim 5 including means for retaining the yoke with its roller pressing the memo and record strips together until said means is released.

8. A memo recorder comprising a casing, a core removably mounted in the casing, a relatively large flange at each end of the core, means for removably mounting a roll of paper in the casing in line with the core with its axis parallel with said core, a strip of paper from said roll extending out of the casing over a portion of the top thereof and back into the casing, and a plurality of guides in the casing for directing the strip of paper between the flanges both before it leaves the casing and after it returns thereto.

9. A device according to claim 8 in which the flanges overlap at least a portion of the roll of paper when it is placed in the casing.

10. A memo recorder comprising a casing, means for removably mounting a roll of paper in the casing, the axis of said roll extending transversely of the casing, a core removably mounted in the casing and extending transversely thereof in line with the roll mounting means, a relatively large flange at each end of the core, a strip of paper from said roll extending out of the casing over a portion of the top thereof and back into the casing, means for turning the roll of paper and the core, a plurality of guides in the casing for directing the strip of paper between the flanges both before it leaves the casing and after it returns thereto, and means for applying tension to said strip of paper.

11. A memo recorder comprising a casing having spaced transverse slots in the top thereof, means for mounting a roll of paper in the casing adjacent one end, a core mounted in the casing near the roll, means for turning the core, a relatively large flange at each end of the core, a roller near the top of the casing spaced from the core, a second roller adjacent the top of the casing between the roll and the core, and means for directing a strip of paper from the roll between the flanges beneath the core, over the first roller, out and in through the slots in the casing, over the second roller, and between the flanges on to the core.

15. 12. A memo recorder comprising a casing, means for removably mounting a roll of paper in the casing, the axis of said roll extending transversely of the casing, a core removably mounted in the casing and extending transversely thereof in line with the roll mounting means, a relatively large flange at each end of the core, a plurality of guides in the casing for directing a record strip from the roll between the flanges, over a portion of the top of the casing, and between the flanges on to the core, means in the casing for receiving another roll of paper from which a memo strip extends out of the casing overlaps at least a portion of the exposed part of the record strip, transfer means between the overlapped strips, and control means for selectively causing the memo strip to move in unison with the record strip.

13. A device according to claim 12 in which the casing has a compartment with a bottom and the memo roll rests on said bottom.

14. A memo recorder comprising a casing, means for removably mounting a roll of paper in the casing, the axis of said roll extending transversely of the casing, a core removably mounted in the casing and extending transversely thereof in line with the roll mounting means, a relatively large flange at each end of the core, a plurality of guides in the casing for directing a record strip from the roll between the flanges, over a portion of the top of the casing, and between the flanges on to the core, means in the casing for receiving another roll of paper from which a memo strip extends out of the casing and overlaps at least a portion of the exposed part of the record strip, transfer means between the overlapped strips, control means for selectively causing the memo strip to move in unison with the record strip, and means for automatically stopping the movement of the memo strip after it has moved a predetermined distance.

15. A memo recorder comprising a casing, means for removably mounting a roll of paper in the casing, the axis of said roll extending transversely of the casing, a core removably mounted in the casing and extending transversely thereof in line with the roll mounting means, a relatively large flange at each end of the core, a plurality of guides in the casing for directing a record strip from the roll between the flanges, over a portion of the top of the casing, and between the flanges on to the core, means in the casing for receiving another roll of paper from which a memo strip extends out of the casing and overlaps at least a portion of the exposed part of the record strip, transfer means between the overlapped strips, a roller in the casing over which the memo and record strips pass before emerging from the casing, and means for selectively pressing the said strips together and

against the roller to cause the memo strip to move in unison with the record strip.

16. A memo recorder comprising a casing, means for removably mounting a roll of paper in the casing, the axis of said roll extending transversely of the casing, a core removably mounted in the casing and extending transversely thereof in line with the roll mounting means, large flange at each end of the core, a plurality of guides in the casing for directing a record strip from the roll between the flanges, over a portion of the top of the casing, and between the flanges on to the core, means in the casing for receiving another roll of paper from which a memo strip extends out of the casing and overlaps at least a portion of the exposed part of the record strip, transfer means between the overlapped strips, a roller in the casing over which the memo and record strips pass before emerging from the casing, a yoke pivotally mounted at one end in the casing beneath the roller, at least one roller, and spring means normally retaining the yoke with its roller away from said first roller, said yoke being movable to cause its roller to press the memo and record strips together and against the first roller.

17. A memo recorder comprising a casing, a core removably mounted in the casing, a relatively large flange at each end of the core, means for removably mounting a roll of paper in the casing in line with the core with its axis parallel with said core, means for turning the roll of paper and the core, a plurality of guides in the casing for directing a record strip from the roll between the flanges, over a portion of the top of the casing, and between the flanges on to the core, means for applying tension to the record strip, means in the casing for receiving another roll of paper from which a memo strip extends out of the casing and overlaps at least a portion of the exposed part of the record strip, transfer means between the overlapped strips, and means for selectively causing the memo strip to move in unison with the record strip.

18. A device according to claim 17 including

means for applying tension to the memo strip.

19. A memo recorder comprising a casing having spaced transverse slots in the top thereof, means for mounting a roll of paper in the casing adjacent one end from which a record strip extends, a core mounted in the casing near the roll, means for turning the core, a relatively large flange at each end of the core, a roller near the top of the casing spaced from the core, a second roller adjacent the top of the casing between the roll and the core, said record strip extending from the roll between the flanges beneath the core, over the first roller, out and in through the slots in the casing, over the second roller, and between the flanges on to the core, means in the casing for receiving another roll of paper from which a memo strip extends out of the casing and overlaps at least a portion of the exposed part of the record strip, transfer means between the overlapped strips, a roller in the casing over which the memo and record strips pass before emerging from the casing, a yoke pivotally mounted at one end in the casing beneath the roller, at least one roller mounted on the yoke above its pivot adjacent the first roller, and a spring means normally retaining the yoke with its roller away from said first roller, said yoke being movable to cause its roller to press the memo and record strips together and against the first roller.
